NECKCHAIN DISPLAY STAND OR SIMILAR ARTICLE

Joseph Antonio Torres, Warwick, R.I., assignor to
Textron Inc.

Continuation-in-part of design application Ser. No.
371,124, June 18, 1973. This application Nov. 22,
1974, Ser. No. 526,111

Term of patent 14 years

Int. Cl. D6—06

U.S. Cl. D6—20

FIG. 1

FIG. 2

FIG. 3

FIG. 4

FIG. 1 is an elevational view of a neckchain display stand embodying my new design;

FIG. 2 is an elevational view showing the side opposite that seen in FIG. 1;

FIG. 3 is a top plan view; and

FIG. 4 is a top perspective view.

This application is a continuation-in-part of my co-pending application Ser. No. D. 371,124, filed June 18, 1973.

I claim:

The ornamental design for a neckchain display stand or similar article, substantially as shown and described.
